FIG. 1

FIG. 2

FIG. 3

FIG. 4

FIG. 5

FIGURE 1 is a front perspective view of a combined pen holder and space condition responsive instrument embodying my new design;

FIGURE 2 is a side view of my design;

FIGURE 3 is a front view of my design;

FIGURE 4 is a top view of my design; and

FIGURE 5 is a rear view of my design.

The phantom showing of the pin in FIGURE 1 has been omitted from the other views for convenience of illustration.

The essential features of my disclosed design reside in the portions shown in full lines in the drawing.

The pen is shown in broken lines for illustrative purposes only.

I claim:

The ornamental design for a combined pen holder and space condition responsive instrument, substantially as shown and described.
